PRIMER FOR INTERNAL-COMBUSTION MOTORS.

1,068,310.

Specification of Letters Patent. Patented July 22, 1913.

Application filed September 18, 1912. Serial No. 720,964.

To all whom it may concern:

Be it known that I, GILMAN W. BROWN, a citizen of the United States, and resident of West Newbury, in the county of Essex and State of Massachusetts, have invented certain new and useful Improvements in Primers for Internal-Combustion Motors, of which the following is a specification.

The present invention relates to a device or apparatus adapted to be applied in connection with any internal combustion motor using liquid hydrocarbon as fuel, and particularly in connection with the motors of automobile vehicles, for so priming the motor that it may be readily started when cold.

The object of the invention is to produce a priming device of such character that it can be located in any position, near to or remote from the motor, and above or below the intake of the motor, and will be equally effective whatever its location.

The invention consists essentially in the combination with a tank for a special volatile liquid fuel, of a means for mixing fuel issuing from such tank with air, and with means for making the device operative or inoperative at will, all combined in a compact unitary structure capable of being mounted in any convenient location on the frame of a motor or of the vehicle equipped with the motor, and having a conduit for leading the mixture to the intake of the motor, as hereinafter more fully and specifically explained.

In the accompanying drawings, Figure 1 represents the preferred embodiment of my invention in longitudinal section shown as applied to an automobile vehicle. Fig. 2 is an end elevation of the same as viewed from the line 2-2 of Fig. 1 looking in the direction of the arrow. Fig. 3 is an enlarged sectional view of the means for mixing the fuel with air. Fig. 4 is a side elevation showing the priming device and the motor of an automobile, illustrating one mode of application of the device.

The same reference characters indicate the same parts in all the figures.

The construction of the device consists preferably of a base or head 10 having a cylindrical wall 11 projecting from one side, constituting one end of a tank or reservoir for the liquid fuel and having a rim 12 on

the other side of the head from the wall 11, 55 inclosing a space which contains an operating lever 13, hereinafter particularly described. At suitable points at the exterior of the rim 12 are perforated ears 14 for the reception of screws or other fastenings used 60 in attaching the device to a support. At one side of the head there is a tubular portion 15 forming a mixing chamber and a guide for a valve, hereinafter described, and terminating in an end wall or head 16. The 65 tubular portion 15 will be hereinafter described as a mixing chamber.

Projecting from the wall 16 into the mixing chamber approximately in the axis thereof is a fuel nozzle 17 having a bore 70 which connects with a passage 18 in the wall or head 16 leading from the space inclosed by the wall 11. A threaded needle valve 19 is screwed through a boss 20 on the outer side of head 16 in line with the bore of the 75 nozzle for regulating the entrance aperture of the bore. A packing gland 21 containing packing surrounds the needle valve and is screwed upon the nipple 20.

From the side of the mixing chamber extends an externally threaded nozzle or nipple 22 having a passage which communicates with the interior of the chamber. Between the nipple 22 and the end wall 16 is a slot 23, or its equivalent, a series of holes, in the 85 side wall of the mixing chamber.

On the opposite side of the head from the parts last described is a guideway 24 open at one end and having an abutment shoulder 25 at the other end in which is contained 90 a plunger 26 for operating the lever 13. Said lever is pivoted between ears 27 on the head 10 and has one of its ends projecting into a transverse slot or notch 28 in the plunger 26. The head 10 with the walls 11 95 and 12, the guides 15 and 24 and the wall 16, fuel nozzle 17 and nipples 20 and 22 are all preferably made as one single metal casting. A cup 29 conveniently made of sheet metal is sweated or otherwise secured at its 100 open end within the end of the circular wall 11 and forms together with said wall and the head 10, an inclosed tank or reservoir for liquid fuel. The device is so mounted on its support, as shown in Fig. 1, that when in 105 place the passage 18 is at the lowest point of the tank, whereby a gravity flow of the liquid through the fuel nozzle 17 may occur

whenever such nozzle is open, as long as any liquid remains in the tank.

In the mixing chamber there is mounted a plug valve 30 which has a sliding fit with-
5 in the walls of said chamber and has a range of movement sufficient to cover and uncover the bore of the nipple 22. This plug valve is longitudinally bored and contains a fuel valve 31, a spring 32, and an abutment plug 33. The fuel valve has a head making a sliding fit in such bore and a portion smaller than the head projecting through a restricted aperture in the end of the plug valve in line with the fuel nozzle. The projecting end portion of the valve member 31 is the fuel valve proper and is tapered so as to have an exact bearing on a flaring surface or valve seat formed at the end of the fuel nozzle, as shown clearly in Fig. 3. The spring 32 reacts on the abutment 33, which is tightly fixed in the valve 30 and presses against the fuel valve 31, tending to hold the latter yieldingly against the seat when the plug valve is in the closed position represented in the drawings.

The parts thus particularly described, located beneath the fuel tank constitute a carbureter for producing a combustible mixture of vaporized liquid fuel and air, of which the nozzle 17 is the fuel inlet, the opening 23 the air inlet, the space inclosed within the part 15 is the mixing chamber, the nipple 22 is the outlet for the combustible mixture, the plug 30 is an air valve 35 permitting or preventing inflow of air to the carbureter and outflow of the mixture therefrom, and the valve 31 is the fuel valve admitting or cutting off the supply of fuel to the mixing chamber. A ring 34 is tightly 40 fitted in the mixing chamber surrounding the outlet end of the fuel nozzle and located between the air inlet and mixture outlet of the carbureter. The interior of this ring is larger than the nozzle, whereby an annular space entirely surrounding the nozzle 45 is provided, but the ring produces a constriction in the air tube adjacent to the outlet of the nozzle, whereby the air passing through the carbureter is caused to travel with great velocity immediately adjacent to the nozzle outlet. The suction of the stream of air flowing through this constriction draws the liquid fuel through the nozzle 50 17 at a rate proportional to the rate at which the air moves, which also is proportional to the suction of the motor and the volume of air drawn into the motor. Thus, by reason of the constriction the proportions of the combustible mixture produced in the 55 carbureter are automatically caused to be proper for efficient combustion under all conditions of duty. More air flowing at a higher speed under heavier suction draws from the nozzle more fuel than does a less quantity of air flowing at a slower speed

under lighter suction. The construction is therefore a means for automatically measuring the fuel and air for varying the rate of flow of the fuel in proportion to the rate of flow of the air. The ring serves the further function of an abutment for the air valve 30, arresting the latter when in closed position.

The end of the air valve remote from the air nozzle is slotted and contains an end of the operating lever 13, which is formed as an eye 13^a. A coupling pin 35 passes through such eye and the adjacent parts of the plug valve, connecting the lever and valve pivotally together. The valves of the carbureter are thus connected through the lever 13 with the plunger 26, previously described, so that movement of said plunger in one direction or the other causes opening or closing of the valves. A spring 36 is contained in the plunger guide 24, preferably as shown in Fig. 1, and tends to close the valves 30 and 31.

When the priming device is mounted as shown in these drawings, it is secured to the dash 37 of the motor vehicle, on the forward side of the dash and beneath the hood covering the motor, the plunger 26 passing through the dash in a position where it can be engaged by the hand or foot of the driver. A pipe 38 is connected with the outlet nipple 22 and leads to any convenient point on the intake 39 of the motor, with the interior of which it makes communication. Thus when the plunger 26 is moved outwardly the fuel and air valves are opened and a combustible mixture is produced in the mixing chamber, which is conducted by the pipe 38 to the motor intake. When the plunger is released, the valves are closed and the combustible mixture is no longer produced and conducted to the motor.

This priming device is independent of the main carbureter of the motor and is only used in starting the motor when the latter is cold. It contains liquid fuel of which the precise nature need not be here disclosed further than that it is sufficiently volatile to vaporize at low temperatures so that even in extremely cold weather a mixture will be produced which can be readily ignited. When the motor has been started, the priming device is shut off and the continued running of the motor is effected by the mixture supplied through the main carbureter.

If it is not practicable to place the priming device in the position shown in the drawing, it may be placed anywhere, whether near or remote from the motor or above or below the point of connection of the intake, in fact in any position from which a pipe may be led to the motor intake. This is made possible by the fact that the combustible mixture is produced

at the point where the supply tank is located, and that the substance conducted to the motor is a gaseous mixture of the proper proportions to produce an explosion when fired. Such gaseous mixture can be conducted to a level above that of the tank as well as below it and through a pipe of whatever length and however bent, and the relation between the mixing chamber and the supply tank is never changed, however the location of the device as a whole may be altered, but the carbureter is always in close proximity to the tank and beneath the same so that flow of fuel to the carbureter is assured as long as a drop remains in the tank. As there is no long communication between the tank and the point of vaporization there is no danger of feeding gas instead of liquid to the mixing point.

Mechanically the device is compact and of simple construction, not liable to derangement and capable of being manufactured at slight cost. A connection with the plunger 26 is made through a cord 40 or the like which may be conducted away so that the primer may be operated from a distant point, for instance, at the point where the driver stands in cranking the motor by hand.

30 I claim:

1. A priming device for internal combustion motors comprising a fuel tank, a mixing chamber formed as a part of the structure of said tank and located beneath the latter, a nozzle extending into said chamber and in communication with the tank, an air valve for controlling the flow of air through the mixing chamber, a fuel valve carried by said air valve and yieldingly actuated to seat against the nozzle outlet when the air valve is closed and actuating means mounted on the tank structure for opening said valves.

2. A priming device comprising a tank, a carbureter beneath the tank and formed in unitary structure therewith, said carbureter including a nozzle in communication with the interior of the tank, a compound valve in the carbureter for permitting and preventing flow of air through the same and emission of fuel from the nozzle, a lever pivoted to the tank structure and connected with said valve, and an actuator mounted on the tank structure and operable to open and close said compound valve.

3. A priming device for internal combustion motors comprising a tank, a carbureter located at the bottom of the tank and having a nozzle communicating with the interior of the tank, a valve movable in line with said nozzle and arranged to seat in the orifice thereof, and an actuating member mounted upon the tank and connected with said valve for opening and closing the same.

4. A priming device for internal combus-

tion motors consisting of a casting shaped to form one end of a fuel tank, a cap joined to said casting to form the balance of the tank, said casting having a tubular portion on its under side forming the mixing chamber of a carbureter provided with an outlet, an end wall and a nozzle in communication with the interior of said tubular portion projecting into such portion, a valve having a sliding fit in said tubular portion and movable to cover and uncover the outlet therefrom, a lever pivoted to the casting and connected with said valve, a guide formed as a part of said casting and a plunger contained movably in said guide and engaged with said lever for moving the latter to open and close said valve.

5. A priming device for internal combustion motors, consisting of a tank or reservoir, a tubular member connected with said tank formed with an end wall and a nozzle extending from such end wall into the interior of such member, said member having an air inlet opening in its side adjacent to the end wall and having an outlet at a point more remote from said wall, the nozzle and end wall having a continuous passage leading into the tank, an air valve fitting slidingly in said tubular member and movable across the outlet thereof, a fuel valve carried by said air valve and movable relatively thereto arranged to seat on the nozzle orifice, yielding means tending to seat said fuel valve, and means for opening and closing the valves.

6. A priming device comprising a tank having an inclosed mixing chamber in unitary connection with an outer wall, said mixing chamber having an inlet and an outlet, and containing a fuel nozzle arranged with its discharge orifice intermediate said inlet and outlet and in communication with the interior of the tank, a valve contained in said mixing chamber adapted to stop said nozzle, and means for operating said valve mounted upon said tank.

7. A priming device comprising a tank having an inclosed mixing chamber in unitary connection with an outer wall, said mixing chamber having an inlet and an outlet and containing a fuel nozzle arranged with its discharge orifice intermediate said inlet and outlet and in communication with the interior of the tank, a valve contained in said mixing chamber adapted to stop said nozzle, a guideway on said tank, a plunger movable in said guideway and a connecting member between said plunger and said valve operable by said plunger to move the valve into position for respectively stopping and unstopping the nozzle.

8. A priming device comprising a tank having an inclosed mixing chamber in unitary connection with an outer wall, said

mixing chamber having an inlet and an outlet, and containing a fuel nozzle arranged with its discharge orifice intermediate said inlet and outlet and in communication with the interior of the tank, a valve contained in said mixing chamber adapted to stop said nozzle, a guideway formed on the wall of the tank opposite to said mixing chamber, a plunger movably mounted in said guideway, and a lever pivoted on an

intermediate wall of the tank and having its arms engaged respectively with said plunger and said valve, whereby said plunger may operate said valve.

In testimony whereof I have affixed my signature, in presence of two witnesses.

GILMAN W. BROWN.
